UNITED STATES PATENT OFFICE

1,977,986

CUT-OFF FOR CIGARETTE-MAKING MACHINES

Robert John Alexander Chandler, London, England, assignor to American Machine & Foundry Company, New York, N. Y., a corporation of New Jersey

Application July 8, 1933, Serial No. 679,529
In Great Britain July 26, 1932

16 Claims. (Cl. 131—37)

This invention relates to cut-offs for continuous rod cigarette-making machines of the type comprising an eccentric edged rotary cutter to which is imparted a movement parallel to the axis of rotation, such that during cutting of the cigarette rod the cutter travels in the same direction as the rod and at substantially the same speed, whereby the cigarette rod is cut in a plane at right-angles to the axis thereof.

- 10 According to a prior arrangement as described in British patent specification No. 353,492, the ledger plate which guides and supports the cigarette rod during cutting is mounted upon the cutter support and thus follows the orbital path 15 of the cutter so that a cutting action is effected during each revolution of the cutter, and further during cutting the cutter and ledger plate both move in the direction of the cigarette rod at the same speed. Moreover, in view of the three-point 20 suspension provided for the cutter and ledger plate mounting it is found that constructional difficulties in aligning and setting up the mounting and also in balancing the revolving masses in order to eliminate vibration, occur.
- 25 An object of the present invention is to provide an improved arrangement of mounting the cutter and ledger plate and control thereof whereby the above difficulties are avoided while retaining the advantage of the previous construction derived by imparting an orbital movement to the ledger plate.

In the cut-off according to the present invention the cutter and ledger plate are moved in independent orbits which intersect one another, the cutter and ledger plate being relatively disposed and the direction of movement being such that they alternately approach and recede from one another.

The orbits are preferably circular and obtained 40 through the agency of crank means by which the cutter shaft and ledger plate are supported.

According to a feature of the invention the speed of revolution of the cutter is such that a cut is effected on each alternate revolution. By 45 such an arrangement the width of the cutter may be increased to double the normal with the consequent flattening of the eccentric edge, resulting in a reduction of the shock to the cigarette rod during cutting thereof.

50 Further features of invention will be herein-after described and defined in the claims.

In the accompanying drawings:—

Figure 1 is a sectional elevation taken through the axis of the driving and supporting shafts.

55 Figure 2 is a front view partly in section,

Figure 3 is an end view showing the cutter and ledger plate, and

Figure 4 is a detail of a clutch.

In carrying the invention into effect according to one convenient mode a pair of spaced drive 60 shafts 10, 11 is provided which are geared together by gear wheels 12, 13 so that they rotate at the same speed but in opposite directions.

The axes of the shafts are located in a vertical plane and these shafts are provided with 65 crank discs 14, 15 carrying crank pins 16, 17 which are set relatively to one another so that when at the maximum and minimum distance apart the axes of the crank pins lie in the before-mentioned vertical plane.

The upper crank pin 16 supports a carriage or frame 18 in which a cutter shaft 19 is journaled so that the axis thereof lies in a horizontal plane. The cutter shaft at one end is provided with 70 clamping discs 20 between which an eccentric edged cutter 21 is adapted to be fixed, the cutter being of the usual thin or wafer type and having a slot 22 adapted to accommodate the shaft 19.

The lower crank pin 17 supports a carriage or frame 23 on which a ledger plate 24 is mounted, 75 the disposition of the plate being such that the cutter will engage the slot in the plate when the cutter and ledger plate approach one another and with the crank pins 16, 17 at their innermost position, it being appreciated that the distance between the shafts 10, 11 and the disposition of the eccentric cutter edge and the ledger plate is such that their circular orbital paths will intersect the desired amount necessary to effect the severing of the cigarette rod. The revolving masses comprising the mountings 18 and 23 are balanced by the 80 balance weights 34, 35 associated with the gears 12 and 13.

In order to maintain the two frames or carriages 85 18 and 23 in their correct relative positions and 90 maintain the axes of the cutter shaft and the ledger plate parallel to one another, one carriage 18 is provided with a pair of guide rods 25 extending towards the other carriage and engaging in 95 guide sleeves 26 mounted upon the other carriage 100 23, the axes of these guide rods and sleeves being at right-angles to the axes of the cutter shaft 19 and the ledger plate 24. In other words, the carriages 18 and 23 are interconnected by telescopic 105 guiding elements so that in effect a single composite framework is provided comprising a pair of units which alternately approach and recede from one another. Obviously, the carriages 18 and 23 could be independent of one another and guided by the provision of duplicate crank shafts mount- 110

ed above and below the drive shafts beforementioned or in horizontal alignment therewith.

The drive to the cutter shaft 19 is effected in the usual manner by means of a bevel gear 27 fixed 5 to the associated crank pin 16 and meshing with a bevel pinion 28 on the cutter shaft, the relative sizes being such as to provide the desired speed of the cutter. In the example illustrated a 2:1 drive is provided so that the cutter rotates 10 two revolutions to each revolution of the shaft 10.

The drive of the crank shafts is effected through suitable gearing from the drive of the cigarette-making machine and preferably such transmission includes a bevel gear 29 carried by a vertical 15 shaft 30 extending below the bed 31 of the machine. The bevel gear 29 meshes with a bevel gear 32 mounted upon the lower crank shaft 11. The bevel gears 29, 32 are located above the bed of the machine within a casing having a removable 20 wall 33 so that they may be readily accessible for changing according to the desired relative speeds of the cigarette machine mechanism and the cut-off.

The bevel gear 32 is connected to the shaft 11 25 by a spring ball or like clutch 36 engaging a depression 37 in a disc 38 keyed to the shaft 11. The depression 37 at one end is inclined as at 39 whereby the shafts 10 and 11 may be moved by hand in the driving direction when it is desired, 30 for instance, to set the sharpening devices (not shown) for the cutter.

On the other hand, during running the spring cup 36 will be forced out of the depression if for any reason stoppage of the cut-off should occur.

35 By the provision of separate mountings for the cutter and ledger plate each of which is mounted upon a single support, alignment of the parts is facilitated and, further, by each mounting revolving in a circuitous orbital path, balancing of 40 the parts may be more readily effected.

It will be appreciated that by speeding up the 45 revolutions of the cutter the width of the blade may be correspondingly increased. For example, by doubling the speed of the cutter to that usually adopted the blade may be of double width. This 50 enables the use of a blade having a flatter curvature to the cutting edge so that the cut through the rod is more gradual, thus reducing the shock to the rod which obtains with narrower eccentric edge cutters. In other words, by the improved 55 arrangement described herein, the conditions of the cut are more like those which obtain with circular cutters.

Sharpening of the cutter may be effected by 55 sharpening means as described and claimed in prior British patent specification No. 292,635.

With the cutter shaft 19 rotating at double the 60 usual speed as described above, the cutter will come into contact with the stationary sharpening element every other revolution owing to the displacement of the cutter parallel to the axis of the cigarette rod.

Having now described my invention, what I 65 claim as new and desire to secure by Letters Patent is:—

1. In a cut-off for cigarette rod machines of the 70 class described, a cutter, a mounting for said cutter, a ledger plate, a mounting for said ledger plate independent of the mounting for the cutter, and means for moving said mountings in independent orbital paths and in opposite directions 75 to cause the cutter and ledger plate alternately to approach and recede from one another to effect a cutting of the cigarette rod.

2. A cut-off for cigarette rod machines of the

class described, comprising a pair of spaced crank shafts, a cutter, a ledger plate, a mounting for the cutter carried on one of said crank shafts, a mounting for the ledger plate carried on the other of said crank shafts, means for driving the crank shafts in opposite directions to cause the cutter and ledger plate alternately to approach and recede from one another, and means coupling the said mountings to maintain the axes of the cutter shaft and ledger plate parallel with the axis of the cigarette rod.

3. A cut-off for cigarette rod machines of the 80 class described, comprising a pair of spaced crank shafts, a cutter, a ledger plate, a mounting for the cutter carried on one of said crank shafts, a mounting for the ledger plate carried on the other of said crank shafts, means for driving the crank shafts in opposite directions to cause the cutter and ledger plate alternately to approach and recede from one another, and telescopic 85 members connecting adjacent ends of the two mountings to maintain the axes of the cutter and ledger plate parallel with the axis of the cigarette rod.

4. A cut-off for cigarette rod machines of the 90 class described, comprising an eccentric edged cutter, a ledger plate, two mountings one for the cutter and the other for the ledger plate, a pair of spaced crank shafts on which the said mountings are respectively carried, means for driving the crank shafts in opposite directions to cause the cutter and ledger plate alternately to approach and recede from one another, and telescopic 95 members connecting adjacent ends of the two mountings to maintain the axes of the cutter and ledger plate parallel with the axis of the cigarette rod.

100

5. A cut-off for cigarette rod machines of the class described, comprising an eccentric edged cutter, a ledger plate, two mountings one for the cutter and the other for the ledger plate, a pair of spaced crank shafts on which the said mountings are respectively carried, means for driving the crank shafts in opposite directions to cause the cutter and ledger plate alternately to approach and recede from one another, and driving means between the cutter and its associated crank shaft for revolving the cutter at double the speed of the said crank shaft to cut the cigarette rod on each alternate revolution of the cutter.

110

5. A cut-off for cigarette rod machines of the class described, comprising an eccentric edged cutter, a ledger plate, two mountings one for the cutter and the other for the ledger plate, a pair of spaced crank shafts on which the said mountings are respectively carried, means for driving the crank shafts in opposite directions to cause the cutter and ledger plate alternately to approach and recede from one another, and driving means between the cutter and its associated crank shaft for revolving the cutter at double the speed of the said crank shaft, and means coupling the said mountings to maintain the axes of the cutter and ledger plate parallel with the axis of the cigarette rod.

120

6. A cut-off of the class described, comprising in combination an eccentric edged cutter for severing a cigarette rod, a ledger plate for supporting and guiding the cigarette rod, two separate mountings one for the cutter and the other for the ledger plate, a pair of spaced crank shafts on which the said mountings are respectively carried, means for driving the crank shafts in opposite directions to move the said mountings in independent orbital paths and in opposite directions, means for revolving the cutter by its associated crank shaft and at double the speed of the said associate crank shaft, and means to maintain the axes of the cutter and the ledger plate parallel to one another.

130

7. A cut-off for cigarette rod machines of the class described, comprising a pair of spaced crank shafts, a cutter, a ledger plate, a mounting for the cutter carried on one of said crank shafts, a mounting for the ledger plate carried on the other of said crank shafts, means for driving the crank shafts in opposite directions from the cigarette rod mechanism to cause the cutter and ledger

plate alternately to approach and recede from one another, a bevel gearing forming part of said driving means, a machine bed above which said bevel gearing is located so that it is readily accessible for changing according to the desired relative speeds of the cigarette rod mechanism and the cut-off, and means coupling the said mountings to maintain the axes of the cutter and ledger plate parallel to one another and with the axis 10 of the cigarette rod.

8. In combination with the cut-off as claimed in claim 7, a spring clutch through which one bevel wheel of said bevel gearing transmits motion.

9. A cut-off for cigarette rod machines of the 15 class described, comprising a pair of spaced crank shafts, a cutter, a ledger plate, two mountings respectively carried on said crank shafts one mounting for the cutter and the other mounting for the ledger plate, transmission mechanism for driving the said crank shafts from the cigarette rod mechanism and in opposite directions to cause the cutter and the ledger plate alternately to approach and recede from one another, bevel gearing in said transmission mechanism, a machine bed above which said bevel gearing is located so that it is readily changeable to obtain the desired relative speeds of the cigarette rod mechanism and the cut-off, and telescopic members connecting adjacent ends of the said two mountings 20 to maintain the axes of the cutter and ledger plate parallel with the axis of the cigarette rod.

10. In combination with the cut-off according to claim 9, driving means between the cutter and its associated crank shaft for revolving the cutter at double the speed of such crank shaft.

11. A cut-off for cigarette rod machines of the 30 class described, comprising a pair of spaced crank shafts, a cutter, a ledger plate, a mounting for the cutter carried on one of said crank shafts, a mounting for the ledger plate carried on the other of said crank shafts, transmission mechanism for driving said crank shafts from the cigarette rod mechanism and in opposite directions to cause the cutter and ledger plate alternately to approach and recede from one another, bevel gearing in said transmission mechanism, a machine bed above which the said bevel gearing is located to be readily accessible for changing according to the desired relative speeds of the cigarette rod mechanism and cut-off, clutch means through which one bevel wheel of said bevel gearing transmits motion, and telescopic members connecting adjacent ends of the said mountings to maintain the axes of the cutter and ledger plate parallel to the axis of the cigarette rod.

12. A cut-off of the class described, comprising in combination an eccentric edged cutter for severing the cigarette rod, a ledger plate for supporting and guiding the cigarette rod, two 40 mountings one for the cutter and the other for the ledger plate, a pair of spaced crank shafts on which the said mountings are respectively car-

ried, transmission mechanism for driving the crank shafts from the cigarette rod mechanism and in opposite directions to cause the cutter and ledger plate alternately to approach and recede from one another, bevel gearing in said transmission mechanism, a machine bed above which said bevel gearing is located, clutch means associated with said bevel gearing through which motion is transmitted, driving means between the cutter and its associated crank shaft for revolving the cutter at double the speed of such crank shaft, and means coupling the said two mountings to maintain the axes of the cutter and ledger plate parallel to the axis of the cigarette rod.

13. A cut-off for cigarette rod machines of the 45 class described, comprising a cutter, a mounting carrying the said cutter, a ledger plate, an independent mounting carrying said ledger plate, a single support carrying the cutter mounting and by which an orbital movement is imparted to the cutter mounting, a single support carrying the ledger plate mounting and by which an orbital movement is imparted to the said ledger plate mounting, and means coupling the cutter mounting and ledger plate mounting together while permitting such mountings to approach and recede from one another as they move in their orbital paths.

14. A composite mounting for the cutter and ledger plate of a cigarette cut-off, comprising a 50 pair of elements, a single rotatable support upon which one of said elements is mounted and by which it is moved in an orbital path, a single rotatable support upon which the other of said elements is mounted and by which it is also moved in an orbital path but in a direction opposite to the first mentioned element, and means coupling the two elements together to maintain their axes parallel to the axis of the cigarette rod.

15. A composite mounting for the cutter and ledger plate of a cigarette cut-off, comprising a 55 pair of mountings, a single rotatable support carrying one of said mountings and by which it is moved in an orbital path, a single rotatable support carrying the other of said mountings and by which it is also moved in an orbital path but in a direction opposite to that of the first mentioned mounting, and telescopic members connecting adjacent ends of the two mountings together to maintain their axes parallel to the axis of the cigarette rod.

16. In a cut-off for cigarette rod machines of the 60 class described, an eccentric edged cutter, a ledger plate for supporting and guiding the cigarette rod, and intergeared crank-actuated means for moving the cutter and ledger plate in independent orbital paths and in opposite directions to cause the cutter and ledger plate alternately to approach and recede from one another to effect a cutting of the cigarette rod.
